BOREHOLE EXPLOSIVE CHARGE

Edwin J. Shimek, Dallas, Tex.

Application November 8, 1945, Serial No. 627,316

6 Claims. (Cl. 102—21.8)

1

This invention relates generally to bore hole explosive charges and will be found particularly useful in seismographic exploration.

In seismographic exploration it is now customary to lower an explosive charge into a bore hole by means of loading poles of a suitable nature to the depth desired by the field technicians. The charge and pole string are so connected that after the charge has reached a predetermined position in the bore hole the loading poles may be detached from the charge and withdrawing from the bore hole. The charge is then exploded by means of conventional equipment including conductors extending down into the bore hole and connected to the charge.

The loading pole is usually connected to the explosive charge by a device which releases the charge when the loading pole is given an abrupt vertical pull. Serious accidents have occurred by reason of the fact that the explosive charge does not remain at the predetermined depth at which it is detached from the loading pole. At times it is moved upwardly by the flow of subsurface water into the bore hole, by the buoyancy provided by the mud column, and at other times it is moved upwardly by the firing line when the latter becomes temporarily entangled with the loading poles as the latter are withdrawn. Whatever may be the cause of the upward movement of the explosive charge the fact is that it does at times move upwardly to a point at or near the surface of the earth and when exploded endangers the lives of the field technicians.

Aside from the danger to the field technicians, in seismograph exploration it is of utmost importance that the charge be exploded at a predetermined and positively known depth because if a charge is exploded elsewhere in the bore hole, a result is obtained which is undesirable, confusing, and misleading to the field and office technicians. For reasons well known to those skilled in the art, it is essential that the charge be exploded at a predetermined and known depth.

The general object of this invention is to provide an explosive charge which may be inserted in a bore hole a predetermined distance and which is provided with means to hold it in that position, movement of the charge outwardly of the bore hole and consequent danger to field technicians and erroneous computations being eliminated.

Other objects will hereinafter appear.

The preferred embodiment of the invention is illustrated in the accompanying drawings in

2

which Fig. 1 is a vertical section of a bore hole with the equipment therein;

Fig. 2 is a side elevation of an explosive partially in its tube;

5 Fig. 3 is a fragmentary vertical section of the tube;

Fig. 4 is a side elevation of two explosives connected by a single tube;

10 Fig. 5 is a fragmentary vertical section of the explosive;

Fig. 6 is a fragmentary vertical section of that part of the tube which is adapted to form wall engaging fingers to prevent movement of the tube in the bore hole;

15 Fig. 7 is a fragmentary sectional elevation disclosing the initial distortion of that part of the tube illustrated by Fig. 6;

Fig. 8 is a fragmentary sectional view illustrating the ultimate distortion of the same; and

20 Fig. 9 is a side elevation of the tube with the wall engaging fingers in their extended positions, some of said fingers being removed to better illustrate the construction thereof.

Fig. 10 is a diagrammatic view illustrating 25 the internal thread of the tube as substantially continuous when the sections of the tube 7 are moved to positions adjacent each other.

Referring to Fig. 1 of the drawing, the bore hole is indicated at 1, the explosive charge at 2, 30 the wall engaging means at 3, the loading pole string at 4, the releasable device to connect the loading pole string 4 with the charge 2 at 5, and the firing line at 6.

It is now customary to lower the charge 2 by 35 means of the loading pole string 4 to a predetermined position in the bore hole 1. The loading pole string 4 is then jerked upwardly to cause the device 5 to release the charge 2 and the loading pole string 4 is then withdrawn from the hole, 40 the charge 2 being held from downward movement from the predetermined position by the firing line 6.

The explosive charge now in use does not 45 embody the wall engaging means 3 shown in Fig. 1 and by reason thereof the explosive charge 2, as hereinabove stated, is frequently moved by one force or another upwardly in the bore hole to a position at or near the surface of the earth, with the dangerous and objectionable results above

50 stated. This invention includes the provision of wall engaging means to positively prevent such upward movement after the explosive charge has reached the predetermined depth.

It will, of course, be understood that the bore 55 hole 1 may be of a depth such that the bottom

thereof is the predetermined depth, in which event the explosive charge 2 will be lowered to and may rest upon the bottom. However, this is not a requisite for the proper functioning of the charge locating means.

Referring to Figs. 2 and 3, the tube is indicated by the numeral 7 and its internal thread by the numeral 8, the explosive charge by the numeral 9 and its external thread by the numeral 10.

In Fig. 4, two explosive charges 9 and one connecting tube 7 are shown, the two explosive charges 9 being threaded into opposite ends of the tube 7.

In Fig. 5 the explosive charge 9 may include a wrapper 9a and explosive mixture 9b.

In Fig. 6 the tube is shown as having internal annular grooves 11 and 12, the distance between these grooves being approximately equal to the pitch of the threads 8, or this distance may be varied so that the variable distance is approximately an integral multiple of the pitch of threads 8. Between these internal annular grooves 11 and 12 is external annular groove 13, which is closer to the groove 12 than it is to the groove 11 so that the fingers 3 hereinafter referred to will be directed outwardly and in the direction of the groove 12, said direction being outwardly of the bore hole when the explosive charge is lowered therein so that outward movement is prevented. It will, of course, be understood that this external groove 13 may be cut at a point equidistant from the internal grooves 11 and 12 so that the fingers 3 will extend radially outwardly at substantially a right-angle to the tube 7, but the preferred embodiment is that just described. It will be apparent that the diameter of the circle defined by the ends of the fingers 3 is a function of the ratio of the distance between external groove 13 and internal groove 12 to the distance between external groove 13 and internal groove 11.

Referring further to Fig. 6, that part of the tube 7 intermediate the internal grooves 11 and 12 has axially disposed circumferentially spaced slits 3a to form the fingers 3 when that part of the tube in which the internal groove 11 is cut is moved toward that part of the tube in which the internal groove 12 is cut, as will hereinafter appear.

Referring now to Fig. 7, this figure illustrates the bending of the tube 7 at points adjacent the internal annular groove 11, the external annular groove 13 and internal annular groove 12 during the initial movement toward each other of the sections of the tube 7 in which the grooves 11 and 12 are cut.

Fig. 8 illustrates the bending of the tube adjacent the grooves 11, 13 and 12 at the completion of the ultimate movement of the sections of the tube 7 having the grooves 11 and 12 toward each other. It will be noted that after such ultimate movement the internal thread 8 of the tube 7 is then substantially continuous.

Fig. 10 illustrates diagrammatically the thread 8 as substantially continuous when the sections of the tube are adjacent each other.

Referring to Fig. 9, this figure illustrates the exterior appearance of the tube 7 after the ultimate movement of the sections of the tube toward each other. It will be obvious from this figure that the fingers 3 have been moved outwardly into a position in which they will engage the wall of the hole (as also illustrated by Fig. 1) and if the usual forces tend to move the explosive charge upwardly the fingers 3 will tend to dig into the

wall of the bore hole and positively prevent upward movement of the explosive charge.

Ordinarily the tube 7 is made of waxed pasteboard or the like so that it is relatively frangible and the explosive charge may be removed by a force exceeding the forces which normally tend to move the explosive charge upwardly. But it will seldom be desired to remove the charge from the bore hole in seismographic operations, the practice being to explode the charge in the hole in any event, in order to avoid possible injury to the field technicians.

While the charge is being loaded into the bore hole the flexible fingers are deflected inwardly along the tube and present little additional cross sectional area to the complete charge. In those holes which are not "clean" and are loaded only with difficulty the use of the catcher neither is desired nor need it be used, as described hereinafter.

It will be noted that the grooves 11, 12 and 13 and the slits 3a, the latter of which as herein-after stated may be cut to a point immediately adjacent the exterior surface, do not objectionably weaken the tube 7. Additionally, the two movable parts of the tube, being threaded on the charge, would have to rotate with respect to each other, or strip the thread, before the tube could change its initial length or collapse in catcher operating position. And so if the field technician does not wish to make use of the fingers 3 in any given instance the tube 7 is quite strong enough to be threaded upon the explosives without rupture.

The tube 7 may be first collapsed by moving the opposite ends toward each other and then threaded upon a single charge while held in the collapsed position since the internal thread is then substantially continuous; or the collapsed tube may be threaded upon a very short length of explosive; or if desired, two explosives may be threaded into a collapsed tube; or a series of explosives and collapsed tubes may be utilized.

The depth of the grooves 11, 12 and 13 in tube 7 may be varied depending upon the material of which tube 7 is made. The depths illustrated are satisfactory when the tube 7 is made of pasteboard or the like. The slits 3a may be cut entirely through the tube 7 or if preferred to a point just beneath the exterior surface of the tube 7. These and other changes will be apparent to those skilled in the art, the invention not being limited to the preferred embodiment herein disclosed.

Having described my invention, I claim:

1. A bore hole explosive charge tube having an internal thread, said tube having two sections movable out of their normal positions to predetermined relative positions, the internal thread of said tube being substantially continuous when said sections are in said normal and relative positions, and that part of said tube between said sections being so constructed that when said sections are moved to said relative positions said part is moved outwardly into a bore hole wall engaging position.

2. A bore hole explosive charge including an explosive having external threads, a tube on said explosive and having internal threads engaging the threads of said explosive, said tubing having circumferentially spaced axial slits, axially spaced internal annular grooves adjacent the ends of said axial slits, and an external annular groove between said internal annular grooves, those portions of said tube on the outside of said internal annular grooves being movable toward each other

to cause those portions of said tube defined by said axial slits to move outwardly and to form fingers to engage the wall of the bore hole to prevent movement of said explosive charge in said bore hole, said internal annular grooves being so spaced that when said portions of said tube are moved toward each other the internal thread of said tube is substantially continuous.

3. A bore hole explosive charge including an explosive having external threads, a tube on said explosive and having internal threads engaging the threads of said explosive, said tubing having circumferentially spaced axial slits, axially spaced internal annular grooves adjacent the ends of said axial slits, and an external annular groove between said internal annular grooves, those portions of said tube on the outside of said internal annular grooves being movable toward each other to cause those portions of said tube defined by said axial slits to move outwardly and to form fingers to engage the wall of the bore hole to prevent movement of said explosive charge in said bore hole, said internal annular grooves being so spaced that when said portions of said tube are moved toward each other the internal thread of said tube is substantially continuous, said external annular groove being closer to one of said internal annular grooves than to the other to cause said fingers to be projected in the direction in which movement of said explosive charge is to be prevented.

4. A casing adapted for use in lodging an explosive charge within a bore hole comprising a tube, internal annular grooves adjacent the ends of the tube, an external annular groove in the tube intermediate the internal grooves and axial slits spaced circumferentially about the tube, said slits extending between the internal grooves, whereby, when the tube is collapsed by axial

movement of the end portions toward each other, the slitted portion is expanded radially, thus providing a container suitable for retaining an explosive charge and wall engaging fingers.

5. A casing adapted for use in lodging an explosive charge within a bore hole comprising a tube having annular weakened portions on its internal surface adjacent the ends of the tube and also having an annular weakened portion on its external surface intermediate the internal weakened portions, the wall of the tube also being weakened along longitudinal lines which extend between the internal weakened portions, whereby when the tube is collapsed by axial movement of the end portions toward each other, the material between the internal weakened portions is expanded radially to form wall-engaging fingers.
6. A bore hole explosive charge tube having a plurality of spaced longitudinal slits in its wall with the ends of said slits terminating short of the ends of the tube, the material between said slits being displaced radially outwardly and folded upon itself to form wall engaging fingers when the tube is collapsed by axial movement of the end portions toward each other.
